UNITED STATES PATENT OFFICE.

WILLIAM C. SEITZ, OF PALMER, NEW YORK.

FOUNTAIN PAINTBRUSH.

Application filed January 26, 1922. Serial No. 531,886.

To all whom it may concern:

Be it known that I, WILLIAM C. SEITZ, a citizen of the United States, residing at Palmer, in the county of Saratoga and State of New York, have invented certain new and useful Improvements in a Fountain Paintbrush, of which the following is a specification.

This invention relates to fountain paint brushes and more particularly to an improved apparatus for use in painting large structures such as bridges, churches, large vessels and steamships and other similar large structures upon which it is difficult for a painter to work with an ordinary brush and bucket.

The primary object of the invention is to provide a structure which will include a reservoir adapted to be mounted upon the back of the workman and connected with a paint brush in a manner that will cause the paint in the reservoir to be automatically supplied to a brush as the workman applies the brush to the surface to be painted.

One of the objects of the invention is to provide a device of this character which will be mechanically operated in a manner that will cause the paint to be evenly distributed to a brush while the device is in operation.

Other objects of the invention will appear upon consideration of the following detail description and accompanying drawings, wherein:

Figure 1 is a view of the entire apparatus constructed in accordance with my invention, and

Figure 2 is a section on an enlarged scale showing the paint reservoir and the mechanical means for ejecting the paint therefrom.

Referring to the drawing by numerals, the supporting structure 1 consists of a relatively light frame work of any suitable dimensions which is equipped with shoulder straps 2 whereby the frame work may be adjusted to the shoulders of the user. A girdle strap 4 is provided to go around the waist of the workman so that the frame work will be properly held in position upon the workman's back.

Supported in the frame is a supporting ring 5 which is circular in form and which supports a semi-circular tube 6 which forms the paint reservoir 7. The tube 6 is at-

tached to the supporting ring 5 in any preferred manner and has one end closed as indicated at 8 and the opposite end open as indicated at 9. The closed end 8 is provided with a passageway 10 which communicates with a supply chamber 11 within which is mounted an agitator 12 in the form of a suitable rotary member equipped with blades mounted upon a shaft 13 which is journaled in the chamber 11 as shown. The shaft 13 is provided at one end with a bearing 14 to properly support the shaft and a spool 15 is mounted upon the shaft to receive a flexible cord 16 which may have its end within reach of the workman so that the spool may be rotated when the cord is pulled. A tension spring 17 has one end fixed and the other end attached to the spool 15 so that when the spool is unwound by pulling the cord 16, the spring 17 will tend to rewind the spool for winding the cord upon the spool thus permitting the operator to give a succession of pulls to the cord 16 whereby the agitator element 12 may be moved to prevent the paint from clogging in the chamber 11. A filler opening 18 is provided with a removable cap whereby the paint chamber or reservoir may be filled and a flexible supply tube or pipe 19 is attached to the chamber 11 as shown so that the paint may be conducted through the pipe 19 to a paint brush 19.

A plunger 21 is adapted to extend into the open end of the reservoir and this plunger is preferably constructed of yieldable rubber material adapted to longitudinally stretch so that its diameter may be decreased when desired. The end of the plunger 21 is connected to a plunger rod 22 of substantially semi-circular formation which has one end as indicated at 23, attached to an operating arm 24 which is rigidly fixed to a centrally located pinion 25 mounted upon a centrally located stud shaft 26. A pinion 25 is in mesh with a large driving gear 27 which operates upon a suitably located shaft and the outer end of this shaft is equipped with a square portion 28 whereby a wrench or other similar tool may be applied to the shaft for turning the gear 27. The gear 27 is equipped with a radially extending arm 29 the outer end of which projects beyond the periphery of the gear 27. This projected end of the arm 29 is attached to two spring retaining rods 30 which are substantially circular in form as shown, and

have their free ends extended through a supporting bearing 31 carried by the frame. The bearing 31 acts as an abutment member for coil springs 32 each of which embraces one of the rods 30. These springs are of the expansion type and when a wrench or tool is applied to the square end 28 of the shaft of the large gear, the arm 29 may be pulled to a position of tightly compressing both of the springs 32 as will be readily apparent from a consideration of the structure shown in Fig. 2 of the drawing. To maintain the springs 32 under compression until the apparatus is to be released, 15 a locking pawl or dog 33 is pivotally mounted on the frame and adapted to engage the pinion 25.

As stated, the piston 21 is of rubber material so that it may be longitudinally expanded to decrease its diameter. The longitudinal expansion or lengthening of the piston 21 is accomplished by a flexible chain 34 which is attached to one end of the piston 21 and passes through guide loops 25 35 carried by the rod 22, the free end of the chain being adapted to be attached to a hook member 36 mounted on the end of the arm 24. By pulling upon the chain 34, the rubber piston 21 may be longitudinally extended to decrease its diameter so that it may be conveniently inserted into the reservoir 7. When the chain is released the rubber piston will expand, thus making a tight joint and preventing any of the paint from leaking 30 35 from the reservoir.

When the apparatus is in use, the frame structure 1 will be strapped upon the back of the painter or workman and he will hold the paint brush in either hand. By releasing dog 33, the springs 32 will be permitted to expand thus imparting a turning movement to the gear 27 which will turn the pinion 25. The pinion 25 carrying the arm 24 will impart a movement to the plunger arm 22 which will push or force the plunger 21 into the paint reservoir 7, thus forcing the paint out through the chamber 11 and to the supply tube 19. The agitator element 12 may be operated to keep the 40 45 50 paint flowing evenly and prevent clogging within the reservoir or chamber 11.

Minor changes may be made in the de-

tails of construction without departing from the spirit of the invention or the scope of the claims hereunto appended.

55 What is claimed is:

1. A device of the character described comprising a frame work, a substantially semi-circular tube forming a paint chamber having one end closed and the other end opened, a plunger element movable into the open end of the said tube, a plunger rod attached to the plunger, a pinion centrally mounted in the frame, a large gear in mesh with the pinion and mounted in the 60 said frame, spring retaining rods, an arm carried by the large gear and attached to one end of the spring retaining rod, coil expansion springs embracing the said spring retaining rods and having engagement with 65 the said arm carried by the large gear, an abutment member for the opposite ends of the said springs, means to manually rotate the said large gear whereby the springs may be compressed, and an operating arm 70 carried by the pinion and attached to one end of the said plunger rod.

75 2. A device of the character described comprising a frame work so constructed as to be attached to the back of an operator, 80 a semi-circular reservoir, a plunger movable in one end of the reservoir, a rod connected to said plunger, an arm for actuating said plunger rod, a pinion secured to said rod, a large gear attached to the frame and 85 in mesh with the pinion, compression springs attached to the large gear, a projecting arm acting against said compression springs, means for rotating the large gear, a tube leading from one end of the 90 reservoir, a brush attached to said tube, and means for controlling the flow of fluid into said brush.

95 3. A device of the character described comprising a semi-circular tube forming a reservoir, a plunger movable in one end of said reservoir, a tube leading from the opposite end of said reservoir, means for agitating liquid in said reservoir, and means for agitating the plunger in the opposite 100 end of the reservoir.

In testimony whereof, I have affixed my signature.

WILLIAM C. SEITZ.
